CINNAMATE ESTERS

Seymour L. Shapiro, Hastings on Hudson, Louis Freedman, Bronxville, and Harold Soloway, Tuckahoe, N.Y., assignors to U.S. Vitamin & Pharmaceutical Corporation, a corporation of Delaware

No Drawing. Filed Apr. 8, 1958, Ser. No. 727,036

6 Claims. (Cl. 260—239)

This invention relates to cinnamate esters of amino alcohols. These esters are particularly useful as anesthetics and the invention will be illustrated by description in connection with such use.

The esters of this present invention are cinnamate esters of β -dialkylamino- α -phenylethanol and may be represented by the formula

wherein R_1 and R_2 are lower alkyl groups or are joined as heterocyclic amino radicals with the attached nitrogen, the carbon content of such groups being not less than 4 carbon atoms and not more than 6 carbon atoms, and R_3 is selected from the group consisting of hydrogen and chlorine. The esters may be used in the formulas shown or as salts thereof with non-toxic acids.

Within these narrow structural limits, relatively non-toxic compounds yielding pronounced anesthetic effects are obtained. Furthermore, under concentrations producing effective anesthesia, a desirable lack of irritancy is noted upon injection.

As compared to the standard procaine, we obtain marked improvement in the therapeutic index for our new anesthetics. Thus, we have raised the therapeutic index of 13, found for procaine in our test method, to as high as 400 and even up to 1670 for our compounds under comparable conditions. One feature of our compounds, therefore, is their low or non-toxicity coupled with unusually effective anesthetic action. Individually, the compounds exhibit toxicities as low as one fifth that of procaine. Coupled with this safety factor of decreased toxicity is the high potency as anesthetics which, in individual cases, is 25-30 times that of procaine. This desirable combination of normally opposed properties will be more clearly reflected in the pharmacological studies reported in Tables I and II.

When employed as a local anesthetic, any suitable method of application known in the art may be used. These compounds, furthermore, may be administered in a surgical lubricant jelly base.

EVALUATION AS ANESTHETICS

The compounds of this invention were evaluated by the method of Chance and Lobstein, J. Pharmacol., 82, 203 (1944), for determining the median effective dose of a local anesthetic when applied to the cornea of a guinea pig eye.

A known concentration of solution of the local anesthetic is applied to both eyes of a guinea pig and the eyes kept bathed with this solution for 2 minutes. The eyes are then blotted to remove excess solution.

Five minutes later, the eyes are tested for the anesthetic effect. A horse hair mounted on a glass rod is used. The hair is pressed against the center of the cornea so that the hair is bent to about the same extent at each application. The hair is applied 10 times to each eye and the process repeated 5 times for the test (total of 100 prods). The result is reported thus: 100 minus the number of blinks=percent anesthesia.

Varying concentrations of the anesthetic agent are used and the percent anesthesia is plotted against concentration. The results are expressed as the ED_{50} in mg./ml. which is the quantity of compound per ml. of solution required to effect 50% anesthesia as established from the plot of concentration vs. percent anesthesia.

The toxicity of the individual compounds was also established by administration subcutaneously (s.c.) to mice, in terms of the minimum dose required to be lethal to mice and expressed as LD_{min} in milligrams of compound per kilogram of mouse.

The therapeutic index was then calculated by dividing the LD_{min} by the ED_{50} , the result being a single figure embracing the anesthetic effectiveness of the compound and its inherent toxicity.

The results are shown in Table I. It will be noted that the compounds show therapeutic indices of 400-1670, as compared to the index of 13 found for procaine, the standard local anesthetic, in comparative tests.

Table I.—Anesthetic potency in guinea pig cornea and toxicity of compounds of the formula

No.	R_1	R_2	R_3	ED_{50} , mg./ml.	LD_{min} , mg./kg., Mice (s.c.)	Therapeutic Index	
						1	2
1.	C_2H_5-	C_2H_5-	H	0.6	400	667	
2.	C_2H_5-	C_2H_5-	Cl	2.5	1,000	400	
3.	$(CH_3)_2CH-$	CH_3-	H	1.5	1,000	667	
4.	$-(CH_2)_6-$		H	0.45	750	1,670	

CONTROLS—COMPOUNDS NOT A PART OF INVENTION

5.	CH_3-	CH_3-	H	5.4	500	93
6.	Procaine			15.0	200	13
7.	Xylocaine			6.8	225	33

An important feature of therapeutic utility is the freedom from irritancy upon injection. Using solutions of equivalent or superior anesthetic potency as compared to the control drugs procaine and xylocaine, the irritancy was established by the "irritancy rating" in percent, and results have been expressed in Table II.

Table II

Compound No.	Concentra- tion, mg./ml.	Irritancy Rating, Percent
2.	3.5	17
3.	2	8
4.	2	0
5.	7	12
6.	20	22
7.	20	31

The irritancy test was done in the following manner:

Procedure.—Four rats used for each compound tested. Backs of rats are shaved very closely. Intradermal injection of test compound (0.20 cc.) is administered to each of 4 rats.

Observations.—Site of injections is observed at 3 intervals—24 hours, 48 hours and 72 hours, post-injection. The degree of irritancy is recorded as follows:

- 0 No irritant effect.
- ± Visible redness.
- ++ Visible redness, induration.
- ++ More extensive redness, induration.
- +++ Maximum lesion, with necrosis.

In determining the "irritancy rating," each plus is scored as 1; ± as 0.5. After 3 observations, the total number of plusses divided by the maximum possible plusses (36)=irritancy rating. Thus, a non-irritant compound has a low irritancy rating while the more irritant the compound, the higher the irritancy rating.

These data clearly reflect the superiority of our compounds as anesthetic agents over the control drugs commonly used clinically. In addition, the importance of the proper selection of

is apparent for high anesthetic potency.

METHOD OF MANUFACTURE

The required amino alcohol intermediates for preparing the basic esters of this invention are prepared according to methods described in the literature (Emerson, J. Am. Chem. Soc., 67, 516 (1945)).

In general, the desired secondary amine, represented by R_1R_2NH , is condensed with an oxide such as styrene oxide, p-chlorostyrene oxide, and the like, such oxides containing the R_3 desired in the final product, as indicated in the reaction below.

The required oxides, in the event that they are not commercially available, are prepared by reaction of a Grignard reagent, containing the R_3 group desired in the finished product, with chloroacetaldehyde (Chem. Abstr., 44, 14461 (1950)). This gives the haloxydrins. These in turn, are dehydrohalogenated to yield the required oxides.

Typical of these steps is the reaction.

Indicative of the class of amino alcohols prepared for use as intermediates in this invention by the general reaction described above, are the following compounds listed in Table III.

Table III.—Intermediate aminoalcohols of the type formula

5	R_1	R_2	R_3	B.p., °C.	Mm. Press.	M.P., °C.
10	C_2H_5-	C_2H_5-	H	136-138	10	-----
	C_2H_5-	C_2H_5-	Cl	110-112	0.15	-----
	$(\text{CH}_2)_2\text{CH}-$	C_2H_5-	OH	115-116	4	57-58
	$-(\text{CH}_2)_4-$		H	-----	-----	66-67
	$-(\text{CH}_2)_5-$		H	-----	-----	-----
	$-(\text{CH}_2)_6-$		H	102-103	0.05	-----

20 The esters described in this invention are prepared by the usual techniques from the appropriate intermediates. Suitably, we use cinnamoyl chloride with an equivalent proportion or a slight excess of the tertiary aminoethyl, either in the absence of solvent or in the presence of an inert organic solvent such as benzene, toluene, ether or acetonitrile. The tertiary aminoethanol selected is one containing R_1 , R_2 and R_3 that are to appear in the finished product. After a suitable reaction period, either at room temperature or at elevated temperatures controlled by the reflux temperature of the solvent, the reaction mixture is separated into products. In most instances, the desired ester of aminoethanol, being basic, appears as the hydrochloride. This salt is readily isolated and purified by recrystallization. Alternatively, if the hydrochloride is not readily crystallizable, it is dissolved in water, alkalinized to liberate the free base of the ester, and the free ester then extracted into an organic solvent such as ether, benzene or chloroform, the organic solvent layer evaporated to dryness, and the product purified after such removal of the solvent by distillation under diminished pressure, the principal fraction being accepted.

30 Salts of the esters are readily prepared by the usual technique as, for example, by neutralizing our esters which are basic, by hydrochloric, hydrobromic, phosphoric, sulfuric, succinic, acetic, tartaric acid, or other non-toxic acid in a suitable solvent such as alcohol, water, ether or benzene. The salts form directly. They are collected on a filter or recovered by evaporation.

40 50 Quaternary salts are prepared by reaction of the basic esters with such quaternizing agents as methyl iodide, methyl sulfate, methyl toluenesulfonate, ethyl bromide, benzyl bromide, allyl bromide and ethyl bromoacetate.

55 The compounds of this invention, "dl" mixtures, have optically active forms, and the individual optically active forms isolated by procedures familiar to those skilled in the art, are to be considered within the purview of this invention.

60 65 The invention will be further illustrated by description in connection with the following specific examples showing the preparation of compounds of the invention. Unless specified to the contrary, references in these examples to removal of volatile solvent means removal by distillation, all temperatures are expressed as °C., and the yields represent percentage of theory.

EXAMPLE 1.—2-(N-METHYL-N-i-PROPYLAMINO)-1-PHENYLETHYL CINNAMATE HYDROCHLORIDE

70 A solution of 6.7 g. (0.04 mole) of cinnamoyl chloride in 50 ml. of benzene was brought to reflux. To this was added 7.7 g. (0.04 mole) of 2-(N-methyl-N-i-propylamino)-1-phenylethanol in 50 ml. of benzene over a period of 15 minutes with stirring and continued reflux. Heating and stirring were continued for 2 hours after addition was complete. On cooling, 10.8 g. (75%) of 75 the hydrochloride of the product separated, melting at

164-165°. Recrystallization from methyl ethyl ketone yielded 8.4 g. (58%), melting at 164-166° (uncorr.).

Analysis.—Calcd. for $C_{21}H_{26}ClNO_2$: C, 70.08; H, 7.28; N, 3.89. Found: C, 69.78; H, 7.10; N, 4.19.

EXAMPLE 2.—2-Hexamethyleneimino-1-phenyl-ethyl cinnamate hydrochloride

This compound was prepared by the method used in Example 1, starting with 6.7 g. (0.04 mole) of cinnamoyl chloride, 8.8 g. (0.04 mole) of 2-hexamethyleneimino-1-phenylethanol and 100 ml. of benzene. There was obtained 14.1 g. (91%) of crude hydrochloride, melting at 195-196°, which was recrystallized from methanol to yield 10.3 g. (67%), melting at 208-210° (uncorr.).

Analysis.—Calcd. for $C_{23}H_{28}ClNO_2$: C, 71.58; H, 7.31; N, 3.63. Found: C, 72.07; H, 7.27; N, 3.93.

In a similar manner, 2-pyrrolidino-1-phenylethyl cinnamate hydrochloride and 2-piperidino-1-phenylethyl cinnamate hydrochloride are prepared from the appropriate reactants.

EXAMPLE 3.—2-Diethylamino-1-(p-chlorophenyl)-ethyl cinnamate hydrochloride

The method of Example 1 was used to prepare this compound, starting with 3.3 g. (0.02 mole) of cinnamoyl chloride, 4.6 g. (0.02 mole) of 2-diethylamino-1-(p-chlorophenyl) ethanol and 100 ml. of benzene. Since the product did not precipitate directly, the solvent was removed at diminished pressure and the residue triturated with dry ether to yield, on filtration, 6.0 g. (76%) of solid which melted at 78-87°. Recrystallization from isopropanol gave 4.1 g. (52%) of the hydrochloride of the product, melting at 93-96° (uncorr.).

Analysis.—Calcd. for $C_{21}H_{25}ClNO_2$: C, 63.96; H, 6.39; N, 3.55. Found: C, 63.16; H, 6.89; N, 3.74.

EXAMPLE 4.—2-Diethylamino-1-phenylethyl cinnamate

The method of Example 1 was used to prepare this compound from 19.3 g. (0.1 mole) of 2-diethylamino-1-phenyl ethanol, 16.6 g. (0.1 mole) of cinnamoyl chloride and 225 ml. of benzene. When no precipitation of hydrochloride could be observed, the solvent was distilled off at diminished pressure and the residue triturated with dry ether. Filtration of the resulting solid gave 31.3 g. (87%) of the hydrochloride of the product melting at 119-124°. This was recrystallized from a mixture of isopropanol and isopropyl ether to yield 26.4 g. (74%), melting at 118-120° (uncorr.).

A portion of the hydrochloride was dissolved in 100 ml. of water, made basic with 40% aqueous sodium hydroxide and the liberated base taken up in 100 ml. of dry ether. The ethereal solution was dried over anhydrous magnesium sulfate and then filtered. Removal of solvent and distillation gave a 34% yield (overall) of the base, boiling at 176-178°/0.28 mm.

Analysis.—Calcd. for $C_{21}H_{25}NO_2$: C, 77.98; H, 7.79; N, 4.33. Found: C, 77.61; H, 7.59; N, 4.30.

Special compositions are made for the administration of the anesthetic in various manners.

For use in infiltration anesthesia, solutions are made to contain, for each ml., 1-50 mg. of the anesthetic agent in salt form, and sodium chloride 0.3-5.0 mg. with a preservative, examples being sodium bisulfate 0.1-2 mg., benzoic acid 0.1-0.3 mg., or chlorobutanol 5 mg., and the whole being diluted q.s. to 1 ml. with distilled water. Preparations are also made including in addition, 1 part of epinephrine to 20,000-50,000 parts of the solution.

Other uses for these anesthetics include such applications as ophthalmic ointments and ointments for rectal disorders. These are prepared using formulations familiar to those skilled in the art.

It is to be understood that it is intended to cover all changes and modifications of the examples of the invention herein chosen for the purpose of illustration which do not constitute departures from the spirit and scope of the invention.

We claim:

1. A cinnamate ester selected from the group consisting of esters of the general formula

and nontoxic mineral acid salts thereof in which esters and salts, $-\text{NR}_1\text{R}_2$ is a tertiary amino radical selected from the groups consisting of lower dialkylamino having a total carbon content of 4-6 atoms and 1-pyrrolidyl, 1-piperidyl and 1-hexamethylenimyl radicals, and R_3 is a component selected from the group consisting of hydrogen and chlorine.

2. The compound of the formula

3. The compound of the formula

4. The compound of the formula

5. The compound of the formula

6. The compound of the formula
